UNITED STATES PATENT OFFICE.

EMIL JOSSE, OF BERLIN-LANKWITZ, AND WILHELM GENSECKE, OF BERLIN-WILMERSDORF, GERMANY.

CONDENSING APPARATUS.

1,223,391.

Specification of Letters Patent. Patented Apr. 24, 1917.

Application filed June 16, 1915. Serial No. 34,517.

To all whom it may concern:

Be it known that we, EMIL JOSSE and WILHELM GENSECKE, citizens of the German Empire, residing at Berlin-Lankwitz and Berlin-Wilmersdorf, respectively, Germany, have invented certain new and useful Improvements in Condensing Apparatus, of which the following is a full, clear, and exact description.

10 The present invention relates to apparatus for producing the additional water required in a distilled state for power generating plants. In modern turbine plants it is possible to obtain an absolutely pure product of condensation, but a part of the water fed to the steam boiler, about 5 to 10% is lost owing to leakage, blowing off of the boilers, etc., and must, of course, be replaced. It is most advantageous if this additional 20 water is absolutely pure distilled water.

Now according to the present invention the distilled water is produced in the following manner:—

The steam is taken from the power engine, 25 for instance, from a steam turbine, preferably from one of the last steps of the same and passed through a vaporizer to the condenser of the power engine. The vapors formed in the vaporizer are also fed to the 30 condenser of the power engine. It is thus evident that for the vaporization the waste steam of the power engine is used, the greatest part of the heat of this waste steam having already been consumed so that consequently 35 a very small amount of heat or energy is required for the production of the product of distillation.

For rendering the present invention more easily intelligible reference is had to the accompanying drawing, which shows an embodiment of an apparatus for carrying the method above referred to into practice.

In the drawing *a* designates the power engine, *b* the waste steam conduit and *c* the

surface condenser, the waste steam being 45 passed to the said condenser through the said conduit *b*. *e* is another conduit through which the raw water to be vaporized is fed to the vaporizer *d*. From one of the last steps of the power engine, for instance, a 50 steam turbine, steam is taken from the outlet port *f* and passed through a conduit *f'* to the vaporizer *d*, in which a pipe arrangement *d'* is provided, and from there through another conduit *f''* and a regulating valve *g* 55 to the condenser *c*. The vapors formed in the vaporizer are fed through a pipe *g* also to the condenser *c*, in which they are deposited and won as a pure product of condensation. Besides the port *f* further outlet ports *h* and *i* may be provided, from which steam of a higher pressure may be taken, which is necessary in such cases where the supply of steam to the vaporizer *d* is to be increased.

60 We claim as our invention:—

In an apparatus for producing distilled additional water in power engine plants the combination of a steam turbine, a conduit for the waste steam, a vaporizer, a pipe for 70 supplying raw water to the said vaporizer; a series of steam outlet ports in the turbine, means for feeding the steam from the turbine through the said outlet ports to the vaporizer and from the vaporizer to the 75 condenser, means for feeding the vapors formed in the vaporizer to the condenser and a regulating organ, for governing the supply of steam from the vaporizer to the condenser, substantially as described.

80 In testimony whereof we affix our signatures in the presence of two witnesses.

EMIL JOSSE.
WILHELM GENSECKE.
